UNITED STATES PATENT OFFICE.

BERT E. KLINE, OF SHELDON, INDIANA.

WRENCH.

No. 823,177.

Specification of Letters Patent.

Patented June 12, 1906.

Application filed October 5, 1905. Serial No. 281,493.

To all whom it may concern:

Be it known that I, BERT E. KLINE, a citizen of the United States, residing at Sheldon, in the county of Allen and State of Indiana, have invented certain new and useful Improvements in Wrenches, of which the following is a specification.

In the type of wrench which is in most general use only a portion of the adjusting-nut is exposed and much difficulty is often experienced owing to the fact that a sufficiently firm grip cannot be obtained thereon in adjusting the wrench.

The object of the present invention is to provide a wrench in which the adjusting-nut is so located as not to interfere with the operation of the wrench and in which the entire periphery thereof is exposed so that a firm grip can be secured thereon.

It also frequently happens that a wrench is employed in connection with a large number of the same-sized nuts; and a further object of the invention is to provide means whereby the jaws of the wrench can be clamped in a fixed position.

For a full description of the invention and the merits thereof and also to acquire a knowledge of the details of construction of the means for effecting the result reference is to be had to the following description and accompanying drawings, in which—

Figure 1 is a view through the handle of my form of wrench. Fig. 2 is a transverse sectional view.

Corresponding and like parts are referred to in the following description and indicated in both the views of the drawings by the same reference characters.

My invention is illustrated in Fig. 1, in which the numeral 1 designates the fixed jaw of the wrench, which is rigidly secured to the hollow stock 2, on the outer end of which the handle 3 is located. The relatively movable jaw 4 of the wrench is made integral with a shank 5, which is slidably mounted within the hollow stock 2 and has its outer end contracted to form a threaded stem 6. At the outer end of the stock 2 the opening therethrough is enlarged to form a circular cavity, within which the cylindrical adjusting-nut 7, which co-operates with the threaded stem 6, is located. The outer end of the cylindrical nut 7 projects from the end of the handle and is provided with a knurled head 8, upon which the operator can obtain a secure grip in ad-

justing the wrench. The outer surface of the adjusting-nut 7 is provided with an annular groove 9, which co-operates with the end of a screw 10, which passes through the handle to hold nut 7 in position.

This invention also provides means for locking the jaws of the wrench in a fixed position. The stem 6 at the outer end of the shank 5 is provided with a longitudinal opening 11, formed with broken or segmental threads 12, 65 which preferably run in an opposite direction to those upon the adjusting-nut 7. A screw 13, passing centrally through the cylindrical nut and having a thumb-piece 14 at its outer end, is provided with similar broken or segmental threads, which co-operate with those in the opening 11.

It will be readily understood that the jaws of the wrench can be moved to any desired position with relation to each other by turning the knurled head 8, and attention is again directed to the fact that owing to the peculiar construction of the cylindrical adjusting-nut 7 the same is enabled to be made of such a length as to eliminate all danger of the stripping of the threads, which has heretofore caused considerable annoyance in wrenches of this type. In order to lock the jaws of the wrench in a fixed position, the screw 13 is then turned so that the broken or segmental 85 threads do not engage with each other and is pushed into the thumb-piece 14 until it strikes against the knurled head 8. The wrench can then be rigidly locked in position by turning the thumb-piece 14 so that the segmental 90 threads are brought into engagement with each other. It will be apparent from the drawings that the screw 13 can be readily removed from the wrench when desired and is not rigidly secured thereto.

Having thus described the invention, what is claimed as new is—

1. In a wrench, the combination of a fixed jaw rigidly secured to a hollow stock, the opening through the stock being enlarged at the outer end to form a cylindrical chamber, a relatively movable jaw connected to a shank which is slidably mounted within the hollow stock, the outer end of the shank being threaded, a cylindrical adjusting-nut located within the before-mentioned chamber and co-operating with the threaded portion of the shank, said adjusting-nut having a thumb-piece projecting from the end of the stock, and means for locking the adjusting-

nut to the shank upon which the movable jaw is mounted to hold the jaws in a fixed position.

2. In a wrench, the combination of a fixed jaw rigidly secured to a hollow stock, the opening through which is enlarged at the outer end to form a cylindrical chamber, a relatively movable jaw connected to a shank which is slidably mounted within the hollow stock, the outer end of the shank being threaded and provided with a longitudinally-disposed threaded opening, a cylindrical adjusting-nut located in the before-mentioned cylindrical chamber and coöperating with the threaded shank on the movable jaw, said adjusting-nut having a head which projects from the end of the stock, and a screw passing through the cylindrical nut and coöperating with the threaded opening in the shank to lock the jaws in a fixed position.
3. In a wrench, the combination of a fixed jaw rigidly secured to a hollow stock, the opening through which is enlarged at the outer end to form a cylindrical chamber, a

relatively movable jaw secured to a shank 25 which is slidably mounted within the hollow stock and has its outer end threaded and provided with a longitudinal opening formed with broken or segmental threads which run in an opposite direction to those on the outer 30 face of the shank, a cylindrical adjusting-nut located within the before-mentioned chamber and coöperating with the threaded shank secured to the movable jaw, said adjusting-nut having a head which projects from the 35 end of the stock, and a screw passing through the adjusting-nut and provided with a thumb-piece and with segmental or broken threads which coöperate with the before-mentioned segmental threads to lock the jaws of the 40 wrench in a fixed position.

In testimony whereof I affix my signature in presence of two witnesses.

BERT E. KLINE. [L. S.]
